AIR REGISTER

George F. Haynes, Brooklyn, N. Y., assignor to
 Robins Dry Dock and Repair Co., Brooklyn,
 N. Y., a corporation of New York

Application July 18, 1934, Serial No. 735,733

7 Claims. (Cl. 158—1.5)

This invention relates to furnaces and my improvements are directed more particularly to the means employed for admitting and controlling the directional flow of air for combustion within the 5 furnace.

It is one of the objects of my invention to provide means for causing air to enter the register in a whirling flow and to be directed in spiral formation rearwardly into the furnace, without the creation 10 of abrupt directional changes.

This object is accomplished by forming the register wall of a series of overlapping louvers or hinged doors which are to be opened inwardly to admit streams of air over their outer surfaces, 15 and curved vanes carried respectively by said doors, said vanes being provided with curvilinear or scoop-like inner surfaces that translate the air streams into a rearwardly directed spiral air flow.

20 The scoop-like vanes are set at an angle which causes the air streams, deflected thereby, to intersect the fuel issuing from an atomizer in a vertical plane adjacent the flame cone or diffuser that is mounted on the burner tube, thereby locating the 25 main combustion zone near the point of fuel issuance. By these means more complete combustion of the fuel occurs at the genesis or root of flame propagation, which results in the creation of a relatively short, bushy flame of high efficiency.

30 My improved register may be composed of sheet metallic material in the interest of lightness in weight as compared with a cast iron construction, this sheet metallic formation also lending itself 35 to relative economy in production.

Other features and advantages of my invention will hereinafter appear.

In the drawings:

Figure 1 is a front elevation of an air register 40 constructed according to my invention and here shown as bolted to a boiler front plate.

Fig. 2 is a side sectional view, taken on the line 2—2 of Fig. 1.

Fig. 3 is a sectional view, taken on the line 3—3 45 of Fig. 2.

Fig. 4 is a sectional detail of the limiting stop assembly, taken on the line 4—4 of Fig. 1.

Fig. 5 is a diagrammatic view showing the hinged doors or sections with their scoop-like 50 vanes in an open position, indicating the flow course of air streams in the register, and

Fig. 6 is a detail of an adjustable vane.

In said figures let 1 indicate a boiler front plate to which is secured, as by bolts 2, the base 55 frame 3 of the air register.

Said frame 3 is of sheet material and is in the form of a hexagonal annulus, having an opening 4 to receive the throat ring 5, which latter is also of sheet material and is constricted rearwardly, said throat ring being the means of communication between the register and furnace interior, through the usual Venturi bricking, which is indicated at X.

The annulus 3 is provided with an inturned, 10 peripheral flange 6 which lies against the boiler plate 1, leaving a clearance between said annulus and plate.

A series of bolts 7 which connect annulus 3 with a front plate 8 of the register are secured thereto by nuts 9 and 10 respectively, the nuts 15 9 and the inner ends of the bolts being accommodated in the clearance aforesaid. The hexagonal shape of base frame 3 permits the bolts 2 to be positioned in the frame apices 11, and allows the assembly upon a boiler front of a number 20 of registers, having similarly shaped base frames, as indicated in dotted lines at 12 on Fig. 1, whereby a plurality of registers can be more compactly accommodated on a boiler front than would be the case if the base frame were circular in form. 25

The wall of the register is composed of a series of hinged doors or segments 13, which may be of sheet material, each shaped, as shown, as a segment of the wall contour, and having at its root a tubular formation, indicated at 14, whereby 30 said doors may respectively be mounted pivotally upon the bolts 7.

Each door is positioned so that its free end normally overlaps inwardly the pivotal or root portion of the next succeeding door, thus restraining it from outward movement, while leaving it free to open inwardly, it being the function of the doors to open in this manner unitedly for the admission of air. It will be appreciated that with the doors open, as indicated for example in 40 Fig. 5, streams of air will enter the register with a circulatory motion, flowing over the outer surfaces of said doors. Each door carries at its inner surface a vane 15, whose inner surface is curvilinear and of scoop-like contour, which sur-

face receives the air stream from the outer surface of the next preceding door and translates the purely circulatory motion thereof into a rearwardly directed spiral flow that surrounds the fuel spray from the atomizer. 50

The front plate 8 of the register which has a central opening 16, is provided with an annular series of concentric slots 17, and a ring 18 that is rotatable about rollers 19, 20, pivoted on plate 8, carries pins 21 which are entered in said slots, 55

to be capable of movement therein. The doors 13 each have an inwardly projecting lug 22 that is provided with an angularly disposed slot 23 and the pins 21 are respectively entered within 5 said slots 23, to the end that the rotation of ring 18, which carries pins 21, will cause said pins, while moving through the concentric slots 17, in fixed plate 8, to either open or close the doors 13 while travelling in the angularly disposed 10 slots 23.

These slots 23 have a slight offset 24 at their forward ends in which ends the pins 21 are located when the doors 13 are closed, these offsets serving as locking means to prevent outside pressure from opening the doors. But with the doors 15 open, and the pins then located in rearward portions of slots 23, the effect of pressure from within the register as by an explosion therein, will be to close the doors and thus prevent expulsion 20 of burning gases into the fire room.

It will be noted that while the rollers 19 are flanged, for positioning the ring 18, the roller 20 25 is plain, but an operating lever 25 for ring 18 is mounted on the same pivot 26 as roller 20 and itself serves to position the ring at that point.

The lever 25 has a longitudinal slot 27 therein, and a pin 28 that projects from ring 18 is entered within said slot so that movement of the lever about its pivot 26 is permitted and will rotate 30 the ring thereby serving to open or close the door.

Adjustably mounted on the ring 18 is a stop device 29 which is adapted to co-act with a pawl 30 that is pivoted at 31 on the front plate 8, said pawl lying in the path of rotation of said stop 35 device to limit its extent of movement and thereby to determine the degree to which ring 18 can be turned in opening the doors 13 to a desired degree. Stop device 29 (see Fig. 4) has a slot 32 therein, and a screw 33, entered through said slot, 40 is engaged in the ring 18, said screw having a collar 34 that binds against the slot wall when device 29 has been suitably adjusted. Also screw 33 has an axial threaded extension 35 outwardly beyond collar 34, and a clamping nut 36, provided with operating wings 37, is screwed upon extension 35 and serves to lock device 29 in its 45 adjusted position.

It will be understood that this adjustable stop device is intended for the purpose of providing 50 means for setting a limit to the extent of opening permitted the doors 13. But, if desired to remove the limitation and permit the doors to be opened their full extent, it is only necessary in accomplishing this purpose to throw back the pawl 30.

Mounted on the front plate 8 is an orificed 55 centre plate 38 from which a tubular portion 39 projects forwardly, and in this tubular portion a burner jacket tube 40 is fitted slidably, said tube 40 being adjustable axially, a locking screw 41 serving to retain it in its adjusted position.

The burner tube 42 is placed in jacket tube 40 60 and has the commonly used elements which are well known in the art. Also the burner tube has the usual atomizing nozzle 43 which is entered within the diffuser 44, said diffuser being carried by jacket tube 40 at its rearward end.

The vanes 15 may either be formed integral 65 with the doors 13, or they may be pivotally connected therewith, to permit relative angular adjustment between the vanes and doors, and enable the angular direction of the air flow rearwardly to be varied. In Fig. 6 there appears such a pivotal arrangement wherein a vane 15 is adjustably fitted to a door 13 as by a pivotal bolt

45, which latter can be loosened when it is desired to vary the angular adjustment of the vane. The dotted line positions of the vane indicate certain adjusted positions of the vane suitable for the desired air flow. 5

From the foregoing description it will be appreciated that air flow and intermixture with fuel in the register are produced by curvilinear, scoop-like surfaces embodied as integral parts of the air admission doors. These surfaces admit air 10 around the fuel spray, practically entirely in rear of the diffuser, the latter being near the fire room end of the air scoops. This method of air admission leaves the register throat unincumbered by obstacles that would tend to hinder air flow, 15 and, as logically would be expected, permit the operation even at an advanced firing rate with low pressure drop through the register.

It is to be understood that while an atomizing oil burner is represented in the drawings for discharge of oil in the register in spray formation, other vaporizable fuels or pulverized coal may equally well be employed. 20

Actually my improved register constitutes a carburetor, because the rearwardly flowing air, 25 in spiral formation, mingles within the register with the fuel spray leaving the atomizer, thus creating a carbureted mixture in the combustion zone.

Variations within the spirit and scope of my 30 invention are equally comprehended by the foregoing disclosure.

I claim:—

1. An air register for use with furnaces having a front wall with an opening therethrough, said register including a base frame having an opening registering with said wall opening, a front plate, a surrounding side wall positioned between said frame and said plate and composed of hinged, inwardly opening, overlapping doors 40 which admit air streams, and vanes carried respectively by said doors, said vanes having curvilinear, scoop-shaped surfaces which direct the entering air streams into a centering and rearwardly moving spiral flow. 45

2. A structure as specified in claim 1 in which the vanes are angularly adjustable.

3. A structure as specified in claim 1 in combination with means for controlling the opening and closing of said doors in unison. 50

4. A structure as specified in claim 1 in combination with means for controlling the opening and closing of said doors in unison, said controlling means permitting said doors to close under the influence of internal pressure while preventing their opening under external pressure. 55

5. An air register for use with furnaces having a front wall with an opening therethrough, said register including a base frame having an opening registering with said wall opening, a front plate, a surrounding side wall positioned between said frame and said plate and composed of hinged, inwardly opening, overlapping doors 60 which admit air streams, vanes carried respectively by said doors, said vanes having curvilinear, scoop-shaped inner surfaces which direct the entering air streams into a centering and rearwardly moving spiral flow, means for controlling the opening and closing of said doors in unison, and means for limiting the extent to which said doors can be opened. 65

6. An air register for use with furnaces having a front wall with an opening therethrough, said register including a base frame having an opening registering with said wall opening, a front 70 doors can be opened. 75

7. An air register for use with furnaces having a front wall with an opening therethrough, said register including a base frame having an opening registering with said wall opening, a front

plate, in spaced relation to said frame, bolts connecting said frame and said plate, doors which are hinged upon said bolts, said doors when closed having overlapping relation to constitute a surrounding wall for the register, and when open admitting air thereinto with circulatory motion, fuel discharge means centrally projected in said register, a diffuser mounted on said fuel discharge means, and inclined, scoop-like vanes carried respectively by said doors that direct the admitted air around the fuel spray, in front of the diffuser.

5

10

7. An air register for use with furnaces having a front wall with an opening therethrough, said register including a base frame provided with a tapering throat ring forming an opening registering with said wall opening, a front plate arranged in spaced relation to said base frame, a plurality of inwardly opening segments disposed between said frame and said plate to constitute a surrounding wall, said segments each provided at its inner surface with means for directing the incoming air streams into a rearwardly moving spiral flow, and fuel discharge means projected axially in said register.
